FLUID PUMP

Seymour W. Litt, Glendale, Calif.

Application October 19, 1945; Serial No. 623,333

2 Claims. (Cl. 230—190)

1

This invention relates generally to fluid displacement mechanisms, and more particularly to manually operated portable pumps of the reciprocating plunger type such as are used for inflating pneumatic tires and a wide variety of pneumatic articles and devices.

An object of this invention is to provide a pump of the above described character whose barrel or cylinder is provided at its lower end with a pivotally mounted foot piece on which the operator steps to anchor the barrel to a supporting surface against shifting thereon during operation of the pump, and has its plunger rod provided with a handle mounted thereon for rocking movement, so that should downward pumping strokes be imparted to the plunger in directions non-parallel to the axis of the barrel, the handle will tilt on the rod rather than react rigidly therethrough to cause binding of the rod in the upper end of the barrel, thus greatly increasing the efficiency of the pump by the lessened frictional resistance to motion of the rod, and reducing wear on the working parts of the pump so as to prolong its useful life.

It is another object of this invention to provide a pump whose movably mounted handle, in addition to precluding binding of the plunger rod in the end of the barrel through which the rod projects, is movable to a non-use position wherein its length is substantially parallel to the length of the rod, so that with the foot piece swung about the barrel to lie along the length of the latter, the pump will present a slender, compact parcel free of lateral projections, for convenient storage in a tool box or compartment of an automobile.

It is a further object of this invention to provide a pump from whose barrel the air being pumped is discharged into a flexible hose secured to the lower end of the barrel and provided with a detachable connector adapted to co-act with the movably mounted handle when in its non-use position, to confine the handle against movement, and with the hose maintained substantially parallel with and alongside of the barrel so that the aforesaid slender parcel free of pronounced lateral projections will be maintained.

It is a still further object of this invention to provide a pump having a lubricating washer mounted on the plunger rod for wiping movement against the wall of the barrel in one direction by the pump plunger, with a buffer spring being mounted on the plunger rod with sufficient security to travel with the rod and move the washer therewith to effect wiping movement of the barrel wall in the opposite direction by the washer,

2

whereby to render the washer capable of lubricating the barrel wall with maximum efficiency.

With these and other objects in view, the invention resides in the combinations, arrangements and functional relationships of elements as set forth in the following specification and particularly pointed out in the appended claims.

In the accompanying drawing:

Figure 1 is a view showing in side elevation, one form of pump embodying this invention;

Figure 2 is a longitudinal sectional view taken generally on the line 2—2 of Figure 1, and with the handle in non-use position;

Figure 3 is a view of the pump in side elevation, and showing the handle in working position;

Figure 4 is an enlarged detail sectional view taken on the line 4—4 of Figure 2; and

Figure 5 is a reduced scale view of the pump in side elevation and showing diagrammatically in full and broken lines, the movement of the handle which takes place under certain conditions of operation.

Referring specifically to the drawing, the invention in its illustrated embodiment comprises an elongated barrel or cylinder B composed of an open-ended tube 10 threaded at its lower end at 11 and screwed into a base fitting 12 having a flat bottom 13 adapted to rest on a support. The base fitting 12 has an air discharge port 14 communicating with the lower end of the tube 10, and has secured thereto by a nipple 15, one end of a length of flexible hose 16 whose other end has a suitable connector 17 for attachment to the valve stem (not shown) of a pneumatic article or device to be inflated.

The upper end of the tube 10 is threaded internally at 18, and has screwed thereinto a cap 19 having an air induction port 20 and a central opening 21 through which slidably works a reciprocable plunger rod 22, the lower end of which is reduced in diameter to provide an annular shoulder 23 and a stud 24 externally threaded to receive a nut 25 which clamps a plunger P on the stud against such shoulder.

The plunger P is composed of a flexible cupped disk 26 confined between metal washers 27 and 28, and adapted to have fluid-sealing engagement with the wall of the barrel during the downstroke of the plunger so as to pump air in advance of the plunger into the hose 16, and to permit air drawn into the barrel by the plunger through the induction port 20 during such downstroke, to pass between the disk 26 and the barrel wall during the following upstroke of the plunger, as is the

usual cycle of operation in a single-acting pump of this type.

A handle H in the form of a bar shaped to fit the hands, is provided medially between its ends with a laterally projecting portion 30 bifurcated to define spaced lugs 31 between which the upper end of the plunger rod 22 is received for pivotal mounting of the handle on the rod by means of a pin 32. The handle can thus be swung on the rod about the axis of the pin 32 to occupy working positions at an angle to the rod as shown in Figures 3 and 4, or a non-use position parallel to the rod at one side thereof as shown in Figure 2. In its non-use position, the rod is received in a longitudinal recess 33 formed in one side of the rod from one end thereof to the space between the pivot lugs 31, so as to bring the handle as close as possible to the rod and thus contribute to the slender parcel which is formed by the pump for storage.

Movement of the handle H from its non-use position, is limited to a predetermined tilted position beyond the transverse or right angular position shown in Figure 3, by a stop shoulder 35 on the handle which is adapted to strike the rod 22. A spring clip 36 of generally U-shape in plan, has its bight portion 37 constricted about the air hose 16 adjacent the end of the latter, so as to be permanently mounted on the hose.

The spring arms 38 of the clip 36 have diverging portions 39 adapted to receive the plunger rod freely therebetween, and have converging portions 40 adapted to engage oppositely projecting shoulders 41 on the handle H when the clip is snapped over the handle in the non-use position of the latter as shown in Figure 4, by spreading the arms 38 under the camming action of the diverging free end portions 42 of the arms with the handle. With the clip 36 applied to the handle, the latter will be releasably retained in its non-use position in proximity to the cap 19 of the barrel B, and will support the flexible hose 16 in a position close to and substantially parallel with the barrel.

A foot piece F preferably constructed of a length of wire bent into generally U-form, has trunnions 45 on the free ends of its arms 46, received in diametric openings in the base fitting 12 to mount the foot piece for pivotal movement to occupy the active position shown in Figures 3 and 5 wherein the handle projects laterally from the barrel, or an inactive position shown in Figures 1 and 2 wherein the barrel is received between the arms 46 of the foot piece. The closed end portion 47 of the arms 46 is laterally bent to form a stop for the foot to prevent slipping of the latter from the foot piece during use of the pump.

Mounted on the plunger rod 22 is a lubricating washer 50 of felt or other suitable material, which is adapted to be moved upwardly by the plunger P during the upstroke of the latter, to wipe lubricant along the internal surface of the barrel. A coil buffer spring 51 which is tapered longitudinally, is mounted on the rod 22 between the washer 50 and the upper end of the rod, and has its larger end bearing against the washer. The smaller end of the spring 51 embraces the rod 22 with sufficient security for the spring to travel with the rod and thus assure that during the downstroke of the plunger, the spring will move the washer downwardly to reversely wipe the barrel surface, thus rendering the washer capable of efficiently spreading lubricant over such surface in the operation of the invention which is as follows:

With parts of the pump in the position shown in Figure 2, the pump forms a long, slender and compact parcel free of such lateral projections as might interfere with storage and removal of the pump from a restricted space. To use the pump, it is only necessary that the clip 36 be released from the handle H to free the latter for adjustment from its non-use position to its working position, and to enable the connector 11 to be applied to the valve stem of the article or device to be inflated.

With the pump occupying a vertical position as shown in Figure 3, one foot of the operator is placed on the foot piece F so that the length of the foot extends transversely with respect to the length of the foot piece, to thus prevent lateral shifting of the lower end of the barrel B. By the provision of the laterally upward projecting end portion 47 of the foot piece, the foot of the operator will be confined against slipping off of the free end of the foot piece, to thereby provide a more secure anchorage for the lower end of the barrel on a supporting surface.

With the handle grasped in both hands of the operator, pumping of air through the barrel B will be effected by vertical reciprocating movement imparted to the handle to correspondingly actuate the plunger P. Should the barrel swing about the axis of the trunnions 45 of the foot piece F during this pumping operation, as is the tendency when pumping against an opposing pressure, the manual force exerted vertically downward upon the handle H will be in a direction non-parallel or at an angle to the axis of the barrel B. Were the handle H rigidly secured to the upper end of the plunger rod 22 in the manner of pumps of the type heretofore proposed, the resulting lateral or horizontal component of the vertical force exerted at an angle to the barrel axis, reacts adversely upon the rod to produce a binding tendency thereof in the opening 21 of the barrel cap 19, thus setting up a resistance to pumping movement of the plunger, and hence reducing the efficiency of the pump, as well as increasing the wear on its working parts.

However, by freely pivoting the handle H at 32 in accordance with the illustrated embodiment of this invention, the handle will be free to rock or tilt and thus yield relatively to the pump rod, with the result that should the barrel B be occupying a tilted position to one side or the other of the perpendicular as shown in full and broken lines, respectively, in Figure 5, the adverse reaction of the rod 22 in the opening 21 will be reduced to a minimum, so that the tendency of the rod to bind in the opening will be correspondingly reduced, thus freeing the rod for its pumping stroke with but negligible frictional resistance from the barrel. Therefore it will be manifest that the pump can be operated with less manual effort to displace fluid with higher efficiency and less wear upon working parts, all with a mechanism of simple, rugged construction.

I claim:

1. A pump of the class described comprising: a barrel; a plunger in the barrel; a rod connected to the plunger and projecting from one end of the barrel; an elongated handle; means pivotally mounting said handle intermediate its ends on said rod to occupy working positions wherein the handle projects on opposite sides of the rod, and a non-use position wherein the handle is disposed substantially parallel to the rod at one side thereof; a flexible air hose connected to the

barrel remotely from said one end thereof and adapted to conduct pumped air from the barrel; and a generally U-shaped spring clip carried by said hose and providing spaced portions between which said rod is received with such portions in latching engagement with said handle to confine the latter in non-use position and support the hose extended at the side of the barrel.

2. A pump of the class described comprising: a barrel; a plunger in the barrel; a rod connected to the plunger and projecting from one end of the barrel; an elongated handle having a laterally projecting bifurcated portion medially between its ends providing spaced lugs between which the outer end of said rod is received; a pin supported by said lugs and passing through the rod to pivotally mount said handle on the rod; said handle having oppositely disposed shoulders; a flexible air hose connected to the barrel; and a generally U-shaped spring clip carried by said hose and defining portions adapted to receive said rod therebetween and to be snapped about said handle in engagement with said shoulders thereof when the handle occupies a non-use position substantially parallel with the rod at one side thereof.
